UNITED STATES PATENT OFFICE.

LOUIS LEVUSSOVE, OF NEW YORK, N. Y.

RINGLET.

1,403,792.

Specification of Letters Patent. Patented Jan. 17, 1922.

Application filed May 12, 1921. Serial No. 468,894.

To all whom it may concern:

Be it known that I, LOUIS LEVUSSOVE, a citizen of the United States, residing at New York, in the county of New York and State 5 of New York, have invented certain new and useful Improvements in Ringlets; and I do hereby declare the following to be a full, clear, and exact description of the invention, such as will enable others skilled in the art 10 to which it appertains to make and use the same.

Heretofore ringlet hair has been manufactured and furnished to the trade. Ringlet hair, or for brevity, ringlets are used for 15 making up other articles, being combed out and otherwise worked for producing the desired articles. The ringlets comprise a means of supplying curled hair to the trade, not being intended for use without alteration. 20 Ringlets as heretofore supplied the trade have been in longitudinal coils with the root and point ends both exposed. The points as a consequence have become snarled, uncurled and damaged resulting in much 25 annoyance, loss of hair and depreciation in value and appearance.

This invention has for its objects to provide a ringlet which will better hold the curl to protect the curled ends of the ringlet; to 30 thus obtain a ringlet which may be made up by the customer with less combing and less waste; to provide a ringlet which will reach the customer smooth and tightly coiled; to avoid pulling out the smaller or point end 35 of the curl in matching the hair; to provide an improved and efficient method of manufacture; to secure simplicity in the manufacture and attractiveness of construction, and to obtain other advantages and results as may be brought out in the following description.

Referring to the accompanying drawing in which like numerals of reference indicate similar parts throughout the several views, 45 Figure 1 is a perspective view of a ringlet manufactured in accordance with my invention; and

Figures 2, 3, 4 and 5 illustrate successive steps in the manufacture of said ringlet.

50 In the specific embodiment of the invention illustrated in said drawing, the reference numeral 1 indicates in general the ringlet. As shown in Figure 1 this ringlet preferably is manufactured so as to provide a curl or coil of hair 2 next the root end of

the ringlet which it is customary to tie as at 3. The other ends of the hair, or points, which normally forms the smaller or free end of the curl or ringlet is arranged in a transverse coil 4. This transverse coil 4 and 60 the longitudinal coil 2 are both integral being formed from the same strands of the hair. The points or normally free ends of the hair are contained within the transverse coil 4, and are thereby protected in the handling of the hair and will maintain the curl 65 therein upon receipt of the ringlet by the customer, firmer and more lasting than ringlet hair which has been heretofore manufactured. Normally the points as heretofore manufactured are exposed, the ends becoming tangled and the curl becoming less and thus making the hair less attractive and less valuable. By the present invention I 70 overcome this difficulty by protecting the points within the transverse coil 4. The coil 4 is upon its exterior composed of continuous strands of hair which form an ample shelter for the points within and obviously will 75 maintain the smooth appearance and will so not be disturbed very readily.

By my improved construction the hair is further protected in that the coil 2 will be the only part which is opened at all during the process of matching the hair, and this 80 is very advantageous in that this handling and matching of the hair will have no ill effects on the points which continue to be protected within the undisturbed coil 4.

My invention also contemplates the method 90 by which the ringlet is produced as above described. The hair is first applied to a mandrel 5, and wound upon it as illustrated in Figure 2. In winding the hair upon the mandrel the points are placed upon the mandrel first and the remaining hair is then wound around it. The points of the hair are accordingly placed inside of the coil at the very outset and obtain the protection of the remaining portion of the hair from the very 95 start. After the hair is thus wound upon the mandrel it is suitably wrapped or tied, see Figure 3, and treated. It is not believed necessary to include herein the various steps in the treatment of the hair while it is so 100 wrapped but suffice it to say that the treatment results in the hair receiving a substantially permanent curl so that when it is drawn off of the mandrel the tendency of it 105 will be to curl up again. Upon the comple- 110

tion of the treatment, the hair is then drawn off of the mandrel, as illustrated in Figure 4, for a part of the length of the hair only, the operator twisting it as it is drawn off. 5 The amount which the hair is withdrawn at this time represents the amount of hair which is required to make the longitudinal coil 2.

The portion of the hair which remains 10 upon the mandrel is for forming the transverse coil 4. This portion of the hair is not removed by unrolling as in the case of the first portion of the hair, instead, the mandrel 5 is slid out from the coil as illustrated in 15 Figure 5. This leaves the coil of the hair 4 just as it was wound upon the mandrel with the points inside and entirely undisturbed. After the hair is tied at its roots, as at 3, the same is ready for the buyer. 20 Obviously detail changes in the manufacture and construction of my improved ringlet may be made in practice without departing from the spirit or scope of the invention and I do not wish to be understood as 25 restricting myself to the exact construction or the precise steps in its manufacture ex-

cept as set forth in the following claims when construed in the light of the prior art.

Having thus described my invention, I claim:—

1. A ringlet comprising a longitudinal coil and a transverse coil at one end of the longitudinal coil integral therewith. 30

2. A ringlet comprising transverse coils having the points of the ringlet protected 35 within one of the coils.

3. The herein described method of manufacturing ringlets comprising winding the hair upon a mandrel and unwinding a portion from the mandrel and sliding the mandrel from within the remaining portion of the coil. 40

4. The herein described method of manufacturing ringlets comprising winding the hair upon a mandrel, treating the hair for 45 producing permanent curl, unwinding a portion of the hair, and sliding the mandrel from within the remaining portion of the hair.

In testimony whereof I affix my signature. 50

LOUIS LEVUSSOVE.
